(57) **CLAIM**

We claim the ornamental design for a vehicle front fascia, as shown and described.

DESCRIPTION

FIG. 1 is a perspective view of a vehicle front fascia; FIG. 2 is top plan view thereof; and,

FIG. 3 is a front elevation view thereof.

The right side view of the vehicle front fascia is omitted because the right side view is identical to the left side view. In particular, the dash-dot (—·—) broken lines demarcate the boundaries of the portions of the vehicle front fascia that form no part of the claimed design.
